UNITED STATES PATENT OFFICE.

LEWIS B. JEFFCOTT, OF NEW YORK, N. Y.

FOLDING BED.

972,537.

Specification of Letters Patent. Patented Oct. 11, 1910.

Application filed March 3, 1910. Serial No. 547,021.

To all whom it may concern:

Be it known that I, LEWIS B. JEFFCOTT, a citizen of the United States, and a resident of the city of New York, borough of Manhattan, in the county and State of New York, have invented a new and Improved Folding Bed, of which the following is a full, clear, and exact description.

The invention relates to folding beds, such 10 as shown and described in the Letters Patent of the United States, No. 941,879, granted to me November 30, 1909.

The object of the present invention is to provide a new and improved folding bed, 15 arranged to permit of holding the mattress and bedding extended in a horizontal position, or one end extended in an inclined position, or to allow of completely folding the bed, when not in use, into a comparatively 20 small space, at the same time accommodating the mattress and bedding between the head and foot rails of the bed. For the purpose mentioned, use is made of a mattress frame having a head, middle and foot 25 sections, pivotally connected with each other, a center support for the middle section and an adjustable folding connection between the head, center support and head frame section, to allow of holding the said 30 head frame section in a horizontal, vertical and inclined position.

A practical embodiment of the invention is represented in the accompanying drawings forming a part of this specification, in 35 which similar characters of reference indicate corresponding parts in all the views.

Figure 1 is a perspective view of the folding bed, showing the head section of the mattress frame in an inclined position; Fig. 40 2 is a similar view of the folding bed in folded position; Fig. 3 is an enlarged cross section of the adjustable connection between the head frame section and center support; and Fig. 4 is a perspective view of the same.

45 The mattress frame A, carrying the mattress B, consists of a head section A¹, a middle section A² and a foot section A³, pivotally connected with each other, the middle section A² of which is secured to and forms 50 part of a center support C. The foot section A³ is pivotally connected near its lower or foot end with a foot D, adapted to rest on the floor, and from the terminal of the foot section A³ rises a foot rail E, as plainly indi-

cated in the drawings, the foot rail forming 55 an integral part of the foot frame section A³. From the head frame section A' depend pivoted uprights G, each pivotally connected at its upper end by a link H with the head I of the bed, and which head is 60 adapted to rest on the floor, the same as the center support C and the foot D, as will be readily understood by reference to Fig. 1. The lower ends of the uprights G are pivotally connected by links J and J' with the 65 head I and the center support C, and the uprights G are provided with vertical slots G', engaged by a clamping bolt K, extending from one upright to the other, as plainly indicated in Fig. 1, see also Fig. 3. On the 70 clamping bolt K, adjacent to each upright G, are pivoted the lower ends of diverging links L and L', of which the link L is pivotally connected with the link H, while the link L' is pivotally connected with the corresponding side of the head frame section A'. When the wing nuts K' of the clamping bolt K are loosened, then the head frame section A' can be readily swung into a horizontal, inclined or vertical position, and when the 75 desired position is reached the wing nuts K' are screwed up, so as to clamp the links L, L' in position, to lock the head frame section A' in the adjusted position. Thus by the arrangement described, the operator is enabled to swing the head frame section A' into a horizontal position at the time the bed is extended, so as to permit use thereof in the usual manner, and when desired the head frame section A' can be swung into an inclined position and locked therein, as indicated in Fig. 1, so as to raise the upper portion of the party using the bed to an inclined position. When it is desired to fold the bed, the head frame section A' is swung up into 90 vertical position and likewise the foot section A³, as indicated in Fig. 2, it being understood that in doing so, the head I is drawn toward the center support C while the foot D is folded onto the foot section A³, 100 and the rail E extends horizontally at the top of the folded bed, and the mattress and bedding are completely inclosed between the head I, the mattress frame A and the foot rail E, as indicated in Fig. 2. It is also understood that when the head frame section A' is swung into an inclined position, the head I of the bed is drawn toward the center 105

support C, so that the upper free end of the head section A' is at all times close to the face of the head I. In order to insure easy swinging upward of the head frame section 5 A', use is made of counterbalancing springs N, secured at their upper ends to the clamping bolt K and at their lower ends to the bottom of the uprights G. When the head frame section A' is extended horizontally, 10 the springs N are under tension, and when it is desired to fold the bed, the springs N, owing to their downward pull on the bolts K and hence on the links L, L', assist the operator in the upward swinging movement of 15 the head frame section A', to insure easy and convenient folding of the bed.

Having thus described my invention, I claim as new and desire to secure by Letters Patent:

20 1. A folding bed, comprising a head, a foot, a mattress frame having a head section, a middle section and a foot section, the sections being pivotally connected one with the other, a center support for the said 25 middle section, and an adjustable folding connection between the said head, center support and head frame section.

2. A folding bed, comprising a head, a foot, a center support, a mattress frame 30 formed of a head section, middle section and foot section, the middle section being fixed on the said center support and the head and foot sections being foldingly connected with the said head and foot, respectively.

35 3. A folding bed, comprising a head, a foot, a center support, a mattress frame formed of a head section, a middle section and a foot section, the sections being pivotally connected with each other, the said 40 middle section being a permanent part of the said center support and the said foot section having a permanent foot rail, an adjustable folding connection between the said head, head frame section and center support, and a folding connection between the 45 said center support and the said foot frame section.

4. A folding bed, comprising a head, a foot, a center support, a mattress frame 50 formed of a head section, middle section and foot section, the sections being pivotally connected with each other, the middle section being attached to the said center support, a link connecting the said foot with the said 55 center support, an upright hung on the said head frame section, links pivotally connecting the lower end of the said upright with the said head and the said center support, and a link connecting the upper end of the 60 said upright with the said head.

5. A folding bed, comprising a head, a foot, a center support, a mattress frame formed of a head section, middle section and foot section, the sections being pivotally

connected with each other, the middle section being attached to the said center support, a link connecting the said foot section with the said center support, an upright hung on the said head frame section, links pivotally connecting the lower end of the 65 said upright with the said head and the said center support, a link connecting the upper end of the said upright with the said head, a clamping bolt slidingly engaging the said upright, and a pair of diverging links pivoted on the said clamping bolt and pivotally connected with the said head frame section and the said link connected with the upper end of the said upright. 70

6. A folding bed having a head, a support, a mattress frame having a section fixed on the said support, and a head section pivoted on the said fixed section, an upright 75 depending from the said head section and having a vertical slot, a connecting link connecting the said head with the upper end of the said upright, a clamping bolt in the said slot, and a pair of diverging links pivotally connected with the clamping bolt and with the said head frame section and 80 the said connecting link respectively.

7. A folding bed, having a head, a support, a mattress frame having a section fixed on the said support and a head section pivoted on the said fixed section, an upright 85 depending from the said head section and having a vertical slot, a connecting link connecting the said head with the upper end of the said upright, a clamping bolt in the said slot, a pair of diverging links pivotally connected with the clamping bolt and with the said head frame section and the said connecting link respectively, and a pair of links 90 connecting the lower end of the said upright with the said head and the said support respectively. 95

8. A folding bed having a head, a support, a mattress frame having a section fixed on the said support and a head section pivoted on the said fixed section, an upright 100 depending from the said head section and having a vertical slot, a connecting link connecting the said head with the upper end of the said upright, a clamping bolt in the said slot, a pair of diverging links pivotally connected with the clamping bolt and with the said head frame section and the said connecting link respectively, a pair of links 105 connecting the lower end of the said upright with the said head and the said support respectively, and a counterbalancing spring connected with the said clamping bolt and the said upright. 110

9. A folding bed having a mattress frame section, a support on which the said frame section is pivoted, an end piece, an upright pivoted on the said frame section, a connecting link connecting the said end piece with 115 120 125

the said upright, a bolt slidingly mounted on the said upright, a spring interposed between the said bolt and the said upright, and a pair of links connected with the said bolt and pivotally connected with the said connecting link and the said frame section.

5 In testimony whereof I have signed my

name to this specification in the presence of two subscribing witnesses.
